SANITARY SELF-CLEANING COMB AND
CASE

William S. Richards, Medford, Mass.

Application June 20, 1944, Serial No. 541,213

4 Claims. (Cl. 132—28)

The present invention relates to new and useful improvements in hair combs, and has for its primary object to provide, in a manner as hereinafter set forth, a device of this character comprising unique cleaning means whereby said device may be conveniently maintained in a thoroughly sanitary condition at all times.

Another very important object of the invention is to provide a device of the aforementioned character which embodies a case of novel construction which is adapted to enclose the comb and cleaning means therefor, and which, further, functions as a handle when said comb is in use.

Other objects of the invention are to provide a sanitary, self-cleaning comb and case of the character described which will be comparatively simple in construction, strong, durable, compact, light in weight and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is a view in side elevation of a device constructed in accordance with the present invention with portions broken away in section.

Figure 2 is a bottom plan view.

Figure 3 is a view in side elevation of the comb and cleaner removed from the case with portions broken away in section.

Figure 4 is a view in transverse section, taken substantially on the line 4—4 of Figure 1.

Figure 5 is a view in transverse section through the comb and cleaner, illustrating the method of cleaning said comb.

Figure 6 is a transverse sectional view, showing the comb in position for use.

Referring now to the drawing in detail, it will be seen that the embodiment of the invention which has been illustrated comprises a horizontally elongated, substantially U-shaped frame 1 of suitable material, preferably plastic. The frame 1 includes a back or bar 2 having depending from its end portions legs 3. Fixed on one of the legs 3 is a finger grip or handle 4. Formed integrally with the bar 2 is a depending, resilient side flange 5, the purpose of which will be presently set forth.

Rotatably mounted between the legs 3 of the frame 1 is a comb 6. The comb 6 comprises a back 7 which is mounted on pivot pins 8 and 9 between the free end portions of the legs 3, said

back also being of any suitable material, preferably plastic. The pin 9 is removable to facilitate removal and replacement of the comb 6 when desired. The comb 6 further includes teeth 10 which are integral with the back 7.

Removably mounted in the frame 1 is a brush 11 for cleaning the comb 6. Immediately adjacent the bar 2 and the flange 5 thereof, the legs 3 of the frame 1 have extending thereinto notches or recesses 12. The brush 11 includes a back 13 in the form of a bar the end portions of which are inserted laterally in the notches or recesses 12 in side-abutting engagement with the resilient flange 5. The brush 11 further includes bristles 14 which are embedded in the back or bar 13.

A relatively flat, elongated case 15 of plastic or other suitable material is provided for the assembly which has thus far been described. The case 15 is closed at one end, as at 16, and open at its other end for slidably receiving the frame 1 with the comb 6 and the brush 11 therein. The bottom of the case 15 has extending thereinto from the open end of said case a longitudinal slot 17 through which the teeth 10 project when the comb 6 is in use.

In use, the frame 1 is withdrawn from the open end of the case 15 through the medium of the handle 4. The comb 6 is then turned one-half of a revolution in the frame 1 for projecting the teeth 10 of said comb away from said frame. The frame 1 is then slipped back into the case 15 with the teeth 10 of the comb projecting through the slot 17. The device is now ready for use, the case 15 functioning as a handle or back for the comb 6 and preventing said comb from turning in the frame 1. To clean the comb, the frame 1 with said comb therein is, of course, withdrawn from the case 15. As suggested by the arrows in Figure 5 of the drawing, the comb 6 is then oscillated through the bristles 14 of the brush 11 for causing said bristles to sweep between said teeth. By reference to Figures 4 and 5, it is noted that the bristles 14 are of a length so that, in the comb-cleaning operation, the ends of the bristles are in contact with the back of the comb and thus sweep across the latter as the comb is oscillated on its pivot pins 8 and 9, thereby not only thoroughly cleaning the lengthwise faces of the comb teeth, but also the intervening crotches at the bases of the teeth. When the cleaning operation has been completed, the teeth 10 of the comb 6 are brought into substantially side-abutting engagement with the bristles 14 and the device may 55 be replaced in the case 15. By unscrewing the

pivot pin 9, the comb 6 may be readily removed from the frame 1 when desired, as, for example, when it is necessary to replace said comb due to breaking of the teeth 10. The brush 11 may be readily removed from the frame 1 by flexing the resilient flange 5 inwardly in a manner to force the back or bar 13 out of the notches or recesses 12.

It is believed that the many advantages of a sanitary, self-cleaning comb and case constructed in accordance with the present invention will be readily understood, and although a preferred embodiment of the device is as illustrated and described, it is to be understood that changes in the details of construction may be resorted to which will fall within the scope of the invention as claimed.

What is claimed is:

1. A device of the class described comprising a substantially U-shaped frame, a comb, including teeth, pivotally mounted in the end legs of said frame for swinging movement about a longitudinal axis to operative and inoperative position, a brush mounted in the frame for engagement by the comb upon oscillation thereof for cleaning between the teeth of said comb and the crotches at the bases of the teeth, and an elongated case for slidably receiving the frame, the comb and the brush, said case having a longitudinal slot therein accommodating the teeth of the comb when said comb is in operative position.

2. A device of the class described comprising a substantially U-shaped frame, a hair comb rotatably mounted in said frame, and a brush mounted in the frame and including bristles engageable with the comb for cleaning between the teeth

thereof and of a length so that their ends sweep in contact with the portions of the comb back in the crotches at the bases of the teeth upon oscillation of said comb in said frame.

3. A device of the class described comprising a frame including a bar and legs on the end portions of said bar, said legs having notches therein adjacent the bar, a brush removably mounted in the frame and including a back having its end portions engaged in the notches, said brush further including bristles mounted on said back, a comb pivotally mounted between the legs and engageable with the bristles of the brush for cleaning thereby, and a resilient element on the frame engageable with the back of the brush for disengaging said back from the notches.

4. A device of the class described comprising a substantially U-shaped frame, a comb pivotally mounted in said frame at the opposite ends thereof for swinging movement about a longitudinal axis into operative and inoperative positions, said comb, when in inoperative position, being folded substantially within the confines of the frame, and an open-ended elongated case for slidably receiving the frame and the comb therewith lengthwise therein, said case having an open-ended longitudinal slot in one longitudinal edge portion thereof, the open end of said slot merging communicably with the adjacent open end of the case in a continuous slotted formation, whereby the teeth of the comb are protruded through said longitudinally slotted portion of the case and the case thereby serves as a hand grasp for manipulation of the comb in use.
